John T. Schillinger

UNITED STATES PATENT OFFICE.

JOHN J. SCHILLINGER, OF WASHINGTON, DISTRICT OF COLUMBIA.

IMPROVEMENT IN PERCUSSION APPARATUS FOR EXPLOSIVE SHELLS.

Specification forming part of Letters Patent No. 37,820, dated March 3, 1863.

To all whom it may concern:

Be it known that I, JOHN J. SCHILLINGER, of Washington, in the District of Columbia, have invented a new and Improved Mode of Igniting the Charge of and Exploding Shells; and I do hereby declare that the following is a full, clear, and exact description of the construction and operation of the same, reference being had to the annexed drawings, making a part of this specification, in which—

Figure 1 is a side view. Fig. 2 is an end view. Fig. 3 is a longitudinal section. Fig. 4 is a transverse section.

Similar letters of reference in each of the several figures indicate corresponding parts.

This invention relates to certain new and useful improvements in the construction of shells, whereby the explosion of the same is greatly facilitated, and also the immediate ignition of the charge of the shell is caused as soon as the shell strikes the ground or any other resisting object.

The nature of my invention consists in dividing the hollow space of a shell into two chambers, one of which will contain the charge of powder and the other will contain a plunger; and my invention consists in the peculiar manner of fastening said plunger to the rear end of the shell.

To enable others skilled in the art to make and use my invention, I will proceed to describe its construction and operation.

The projectile A, of cast-iron or cast-steel, and any agreeable shape—in our case of cylindro-conical form—may have a base-ring B, of brass, lead, or other metal, of sufficient softness to expand into the grooves of rifled ordnance, which ring B may be shaped as shown in section on Fig. 3. This projectile A is divided into two chambers, E and F, (see Fig. 3,) separated by the collar I, provided to receive a short cylindrical screw, D, which screw has to carry the piston or nipple H, on which the percussion - cap i will be placed. The chamber E is intended to receive the charge of powder, and the chamber F is intended to contain a plunger, G, of a cylindrical or little tapering form. A short cylindrical screw, C, at the lower end of the projectile, closes the chamber F after the insertion of the plunger G. Both short screws D and C are provided with key-holes a a b b, to

enable the screwing in and out by means of a common key. The chamber F is provided with four or more cavities, leaving the ribs m m m m, to facilitate the explosion of the lower or rear part of the projectile; after the short cylindrical screw D has been driven into chamber F by the gaseous products of the inflamed powder-charge of chamber E. The lower or rear end of the projectile A is perforated by two oblique holes, h h, of small diameters, uniformly inclined toward the axis of the projectile, to allow the insertion of a cord of more or less thickness, according to the size of the projectile and that of the plunger G. Screw D and the termination of chamber F are provided with projecting rings or collars g g and f f, to prevent the screws D and C to be screwed in too far. The plunger G is fastened to and kept in its position in the recess c of screw C by a cord, k k k, passing through the cylindrical perforations h h around the head of the plunger G, and fastened outside of the shell by a knot, l. This cord k k k may be impregnated with saltpeter or any other substance favoring burning, if found necessary.

It will easily be understood that when a cannon loaded with my projectile will be discharged the portion l of cord k k k, being outside of the projectile and exposed to the inflamed gunpowder of the cannon, will be burned, and therefore the fastening of plunger G destroyed. The plunger G will be carried with the projectile, assuming the same velocity and a corresponding momentum. As soon as the projectile strikes the ground or the object at which it has been fired, the plunger G will move forward on the percussion-cap, and by a stroke corresponding to the momentum assumed ignite the charge of powder in chamber E, exploding consequently the projectile.

I do not limit myself to a certain shape of projectile, or to a peculiar form of plunger; nor do I limit myself to a certain material for the cord holding the plunger in its proper position before the projectile is fired.

I do not claim the employment of a plunger, knowing that it has been used before; but

What I claim as new and of my invention, and want to secure by Letters Patent, is—

1. Dividing the interior space of a shell or

the hollow part of a projectile into two separate chambers, one containing the charge of powder, the other containing a plunger, when the said plunger is secured to the shell, as hereinbefore specified.

2. Fastening the said plunger to the end or rear part of the shell or projectile by means

of a combustible cord, in the manner and for the purpose substantially as herein described.

JOHN J. SCHILLINGER.
